L. S. LIEBERMAN

DOOR LOCK

Filed June 11, 1927

Fig:2.

UNITED STATES PATENT OFFICE.

LEO S. LIEBERMAN, OF NEW YORK, N. Y.

DOOR LOCK.

Application filed June 11, 1927. Serial No. 198,029.

This invention relates to door locks.

In apartment houses or tenements it is desirable to provide a door lock for the dumb waiters that cannot be readily forced and one that will automatically operate as a latch when the door is closed. A further requirement is that the lock cannot be easily "picked" or opened from the outside. In factories where a door must be securely fastened and yet permit of the quick opening in case of fire or for use in garages a lock having the same requirements is likewise desirable.

One of the objects of this invention is to provide a door lock that will securely fasten the door. Another object of the invention is to provide a door lock that will latch the door in a closed position upon the closing of the door. Still another object of the invention is to provide a door lock that cannot be easily forced or "picked" from the outside. Still another object of the invention is to provide a door latch that can be locked in closed position.

Figure 1 is a view in elevation of a door lock embodying the principles of my invention.

Figure 2 is a view in elevation partly in section along the line 2, 2, Figure 1, looking in the direction of the arrows.

Figure 3 is a modified view of the lock having parts broken off and operable from the outside by a key.

Figure 4 is a view in section along the line 4, 4, of Figure 3, looking in the direction of the arrows.

In carrying out my invention I propose to provide a door lock 1 comprising three bolts 2, 3, and 4, pivotally connected at 5, 6, and 7, within housing 8 by links 9 and 10.

Links 9 and 10 form a toggle lever. Pivotal connection 6 has secured thereto a spring 11 which is also secured to a lug 12 at its other end in housing 8. A lock 13 is adapted to slide within housing 8 between pivotal connection 6 and the side wall of housing 8 to prevent the sliding motion of pivotal connection 6 and the consequent withdrawal of bolts 2, 3 and 4, from seats 15, 16, 17.

Lock 13 comprises plate 13', button 14, spring 18 and rivet 19. Spring 18 is secured to plate 13' and is between 13' and the front face of housing 8 and functions to hold lock 13 in open or closed position.

Rivet shank 20 operates in slot 21 of housing 8. Bolts 2 and 3 operate through guides

22, 23, secured by screws 24, 25, to door 26. Housing 8 is likewise secured by screws 27 to door 26. In alignment with the holes of guides 24, 25, are seats 15 and 17 in plates 28 and 29 secured by screws 30 to the jamb 31 of the door. Plates 28 and 29 have bent over tongues 32, 33, co-operating with the bevelled ends of rods 2 and 3, to repress the rods 2 and 3 towards one another against the action of the spring 11 in closing the door to permit of the bolts entering seats 15 and 17 and likewise plate 34 secured by screws 30 to jamb 31 and provided with tongue 35 functions in a similar manner for bolt 4 to seat in seat 16.

In the operation of the device upon the closing of the door bolts 2, 3 and 4, are forced into housing 8 by the co-action of tongues 32, 33 and 35, against the bevelled ends of the bolts and of spring 11, which latter forces the bolts into their seats upon the closure of the door. Button 14 is then shifted in slot 20 to a dogging position and the door is locked. When it is desired to open the door button 14 is moved to open position, handle 37 is pulled horizontally away from the door jamb and bolts 2, 3 and 4 are withdrawn from seats 15, 16 and 17.

In instances where it is necessary to open the door from the outside the modified form of the device can be used. The modified form of the device is the same in construction except that I provide any well known cylinder lock 38 having a lug 39 secured to barrel 40 of lock 38. Lug 39 is adapted, when barrel 40 is rotated, to bear against pivotal connection 6' to withdraw bolts 2, 3, and 4. In the drawing lock 13 is omitted in the modified form although it also could be used.

It should be noted that the toggle lever arrangement permits of a relatively light spring and a secure locking of the bolts.

It will thus be seen that I have invented a door lock that is simple in construction and by reason of the three bolts which secure the door to the frame at top, bottom and on the side is one that is not easily forced. The form of linkage is such as to permit of easy operation and as it is all enclosed in a housing is of neat appearance. The means for locking the mechanism is not only secure but likewise of simple construction.

Although I have shown its application to a dumb waiter door its use has a wide range.

What I claim is:

1. In a door locking device, a plurality of bolts, said bolts pivotally connected by links within a housing, a spring in said housing, a lug, said spring connected to one of said pivotal connections of said links and to said lug, a plate in said housing adapted to be manually operated to prevent motion of said links.
- 10 2. In a door locking device in combination, a plurality of plates secured to the door jamb, said plates having bolt seats and tongue bolt guides, a plurality of bolts in alignment with said bolt seats and adapted to seat therein, guides in alignment with said bolt seats, a plurality of bolts operating in said guides, a housing secured to the door, said bolts terminating within said housing, links pivotally connected to the ends of said bolts in said housing, spring means secured to said links to normally maintain said bolts in extended position, and means to lock said bolts in extended position.
- 15 3. In a door locking device in combination, a plurality of plates secured to the door jamb, said plates having bolt seats and tongue bolt guides, a plurality of bolts in alignment with said bolt seats and adapted to seat therein, guides in alignment with said bolt seats, a plurality of bolts operating in said guides, a housing secured to the door, 55 said bolts terminating within said housing, links pivotally connected to the ends of said bolts in said housing, spring means secured to said links to normally maintain said bolts in extended position, and means for locking 60 said bolts in extended position, said means comprising a plate, a spring secured to said plate between said plate and said housing, a rivet for said plate having its shank passing through said housing and terminating 65 in a manually operatable button exteriorly of said housing and a slot in the face of said housing for the movement of said shank.
- 20 4. In a door locking device in combination, a plurality of plates secured to the door jamb, said plates having bolt seats and tongue bolt guides, a plurality of bolts in alignment with said bolt seats and adapted to seat therein, guides in alignment with said bolt seats, a plurality of bolts operating in said guides, a housing secured to the door, 70 said bolts terminating within said housing, links pivotally connected to the ends of said bolts in said housing, spring means secured to said links to normally maintain said bolts in extended position, and means for manually locking said bolts in extended position and manual means for retracting said bolts.
- 25 5. In a door locking device in combination, a plurality of plates secured to the door jamb, said plates having bolt seats and tongue bolt guides, a plurality of bolts in alignment with said bolt seats and adapted to seat therein, guides in alignment with said bolt seats, a plurality of bolts operating in said guides, a housing secured to the door, 75 said bolts terminating within said housing, links pivotally connected to the ends of said bolts in said housing, spring means secured to said links to normally maintain said bolts in extended position, and means for locking said bolts in extended position, said means comprising a plate, a spring secured to said plate between said plate and said housing, a rivet for said plate having its shank passing through said housing and terminating in a manually operatable button exteriorly of said housing and a slot in the face of said housing for the movement of said shank.

Signed at New York, in the county of New York and State of New York, this 7th day of June, A. D. 1927.

LEO S. LIEBERMAN.
